Primary Examiner — Cathron C Brooks

(74) Attorney, Agent, or Firm — Donald J. Ersler

(57) **CLAIM**

The ornamental design for a transfer bar, as shown and described.

DESCRIPTION

FIG. 1 is a perspective view of a transfer bar, incorporating our new design;

FIG. 2 is a front view thereof;

FIG. 3 is a left side view thereof;

FIG. 4 is a rear view thereof;

FIG. 5 is a right side view thereof;

FIG. 6 is a top plan view thereof; and,

FIG. 7 is a bottom plan view thereof.

The broken lines shown in the drawings illustrate portions of the transfer bar that form no part of the claimed invention.
